UNITED STATES PATENT OFFICE.

SAMUEL T. WELLMAN, OF CLEVELAND, OHIO.

APPARATUS FOR CHARGING AND DRAWING FURNACES.

SPECIFICATION forming part of Letters Patent No. 394,419, dated December 11, 1888.
Application filed January 30, 1888. Serial No. 262,377. (No model.)

To all whom it may concern:

Be it known that I, SAMUEL T. WELLMAN, of Cleveland, in the county of Cuyahoga and State of Ohio, have invented certain new and useful Improvements in Apparatus for Charging and Drawing Furnaces; and I do hereby declare the following to be a full, clear, and exact description of the invention, such as will enable others skilled in the art to which it pertains to make and use the same.

My invention relates to apparatus for charging and drawing furnaces, such apparatus being mounted on a car adapted to be moved along in front of the line of furnaces, the grappling mechanism being operated by hydraulic rams, to the end that, for instance, ingots of any size may be lifted from a car, charged and drawn to and from the respective furnaces, and delivered onto the table of the reducing-rolls with dispatch and with only such manual labor as is necessary in manipulating the valves of the rams and of the transferring-engine.

My invention also relates to details of construction hereinafter described, and pointed out in the claims.

In the accompanying drawings, Figure 1 is a side elevation, partly in section, portions being broken away to show the construction; and Fig. 2 is an accompanying plan, partly in section. Fig. 3 is a left-hand end elevation. Fig. 4 is an elevation in transverse section on line xx , Fig. 1. Fig. 5 is a plan, partly in section, of the plant. Fig. 6 is a corresponding elevation, the furnace being shown in section.

In carrying out my invention any number of furnaces A are located in line, with tracks a just in front of the furnaces, on which tracks ordinary cars, a' , operate in bringing, for instance, ingots A² or other material with which to charge the different furnaces.

B are tracks widely separated, on which operates a broad car, B', on which latter car is mounted the apparatus for charging and drawing the furnace, this car being constructed, preferably, as follows: Heavy I-beams C are arranged, as shown, in pairs, having respectively boxes c attached, in which are journaled the axles of the respective wheels C'. On top, 45 extending crosswise and rigidly secured to these I-beams, are heavy channel-bars C², the smooth side of the latter presenting inward.

These channel-bars and I-beams form, in the main, the frame-work of this car. Connected with the rear portion of channel-bars C² are 55 uprights D for supporting platforms D', on which latter the operator is posted. To the forward portion of bars C² are attached uprights F for attaching the water cylinder or ram F'. Next inside of bars C² are located 60 I-beams E. These latter are connected in front and in rear, forming a rigid frame, which, for convenience, I will hereinafter mention as "frame E⁴." The rear connection of beams E is shaft E', the projecting ends of which are 65 pivoted at e in the frame-work of the car, and the forward connection is shaft E², on which latter are mounted the flanged wheels E³. The protruding ends of shaft E² are connected by pitmen f with cross-head f' of ram F'. By operating the ram the frame E⁴ may be tilted on its pivotal bearings and raised or lowered, as may be required.

G are I-beams rigidly connected, and hereinafter mentioned as "frame G," the forward 75 portion thereof resting on wheels E³. The rear end of frame G is provided with wheels G', the latter traveling on beams E; also are provided wheels G², that engage the under surface of beams E to hold down the rear end 80 of frame G. The axle of wheels G² is connected by side arms, g, with the axle of wheels G', and is further supported by a hanger, g', the latter being secured to frame G. (See Fig. 4.) Between bars G, and rigidly attached 85 to the latter, is water cylinder or ram H, the plunger H' of the latter being attached at H² to an attachment, e², of frame E⁴.

By operating ram H frame G is run forward or retarded rearward, as may be required, in 90 charging or drawing a furnace or for delivering an ingot onto table A' of the reducing-mill. On top and near the forward end of frame G is attached a heavy plate, I, and to this plate, by means of studs I', are fulcrumed 95 the grappling levers or tongs J, these levers being arranged side by side, as shown. The forward ends of these levers are offset, first outward and then downward, (see Figs. 1 and 3,) so as to span when distended an ingot of 100 large size, the extremes of these levers being provided with prods j, or other suitable device, arranged on their inner faces, for grasping the ingots. Levers J in plan are shaped

substantially as shown in Fig. 2, the rear ends thereof trending outward and forming substantially lateral inclines.

K is a short ram mounted on and rigidly secured to frame G, the plunger k of this ram extending forward between and being rigidly attached to plates L, the latter extending forward, respectively, over and under the rearward portion of levers J, these two plates forming substantially a cross-head. Connected with plates L are vertical studs l and l', the former being located between and engaging the inner faces of levers J to separate the rear ends of these levers with the forward movement of plunger k. Studs l' are located outside and engage the outer faces of these levers to retract the same with the rearward movement of plunger k. By operating plunger k rearward the forward ends of levers J are spread apart, and by actuating plunger k forward the forward ends of levers J are made to approach each other to clamp the ingot or other body, and these levers maintain such clamping position so long as the water-pressure forward is left in ram K.

To recapitulate: By operating ram F' the grappling device is raised or lowered, as required, and by operating ram H the grappling device is moved forward and rearward, and by operating ram K the grappling-levers are made to grasp or release the load. At least a portion of pipes h' and k', leading to the respective rams H and K, and the corresponding return-pipe, are flexible. Pipes f², leading to ram F', and the return-pipe for this ram, may be inflexible. These different supply-pipes connect with the general supply-pipe M, with valves h², k², and f³, of ordinary construction for such purpose, for operating the different rams, the levers of these different valves being within easy reach of the operator. Pipe M connects with a flexible pipe (not shown) that admits of the car traveling along the tracks B. The different return-pipes connect with a common discharge-pipe, M', and the latter may discharge onto the ground; or the water may be conducted from this pipe by means of a flexible pipe to a tank. It is not considered necessary to show or describe these different pipes in detail, as I claim no invention on the same, and the arrangements of such pipes for such purpose are well understood in connection with hydraulic rams.

55 Cables N have their respective ends attached to car B', these cables being wound around drums N' with a sufficient number of convolutions each to prevent the cables slipping on the drums. These drums are driven by engines P, the latter having the usual reversing mechanism attached, so that the starting and reversing of the engines are effected by a single lever, p.

A small cable, R, is attached to reversing lever p of the engine. This cable may be supported on sheave r, with weights r' attached at the respective ends of the cable; or the ca-

ble may be endless and mounted on sheaves, if so preferred. This cable passes just in front of the operator on platform D', and by means of which the operator has full control of the shifting-engine. By operating drums N' in the one direction or the other, car B' is moved along the tracks B as may be required.

In operating the apparatus the ingots are brought on car a' in front of the furnace, where they are wanted. The grappling-levers or "tongs," as they are more commonly called, are lowered and made to grasp the ingots, after which the tongs are raised and run forward to deliver the ingots into the furnace, whereupon the tongs are lowered until the ingots rest upon the bottom of the furnace, after which the forward ends of the tongs are separated to release the ingot, and the tongs are again raised a trifle and backed out of the furnace. In drawing the furnace the tongs are run into the furnace, lowered, and made to grasp the ingot, then raised until the ingot will clear the furnace-bottom, and then backed out of the furnace, after which the car B' is run along tracks B in front of table A', where the ingots are deposited.

By means of this apparatus a great saving is effected in time, labor, and wear and tear of the furnace over the old method of charging and drawing furnaces; also, the furnaces are set in line, so as to occupy as little space as possible.

What I claim is—

1. In an apparatus for charging and drawing furnaces, the combination, with a car, of a tilting frame thereon, the latter carrying longitudinally - movable grappling devices, substantially as set forth.

2. In an apparatus, the combination, with a car, of a tilting frame thereon, a sliding frame mounted on said tilting frame, and grappling devices carried by said sliding frame, substantially as set forth.

3. The combination, with furnaces, car, and apparatus for moving the car along in front of the furnaces, of tilting frame mounted on the car, and a ram for operating such tilting frame, the latter having the grappling devices operatively mounted thereon, substantially as set forth.

4. The combination, with car and mechanism for moving the car, of tilting frame mounted on the car, ram for operating such tilting frame, a traveling frame mounted on the tilting frame, and a ram for operating the traveling frame, the latter having connected therewith the grappling devices, substantially as set forth.

5. The combination, with car, tilting and traveling frames, and rams for operating the same, substantially as indicated, of grappling-levers fulcrumed to the traveling frame, and a ram for operating such grappling-levers in grasping and releasing the load, substantially as set forth.

6. The combination, with grappling-levers arranged side by side and separately ful-

crumed midway thereof, said levers having outward trend, forming substantially lateral inclines, of ram for operating such grappling-levers, and a cross-head being connected to

5 the plunger of such ram, said cross-head having studs arranged inside and outside the inclined portion of such grappling-levers, substantially as set forth.

10 7. The combination, with grappling-levers arranged side by side and separately fulcrumed, so as to operate in a horizontal plane, the free end of such levers being offset first

outward and then downward, substantially as indicated, of ram and connected mechanism, substantially as shown, for operating such 15 levers, substantially as set forth.

In testimony whereof I sign this specification, in the presence of two witnesses, this 2d day of December, 1887.

SAMUEL T. WELLMAN.
